FIGURE 1 is a side elevation of a combined handle and motor housing for portable power tools showing my new design;

FIGURE 2 is a top plan view thereof;

FIGURE 3 is an elevation taken from the right side of FIGURE 1;

FIGURE 4 is a view looking in the direction of arrows 4-4 of FIG. 1, the handle being omitted to better illustrate the configuration of the motor housing;

FIGURE 5 is a sectional view taken along line 5-5 of FIGURE 1.

The fragmentary showing of a power cord in FIGURE 1 is for illustrative purposes only.

We claim:

The ornamental design for a combined handle and

motor housing for portable power tools, substantially as shown and described.
